DESIGN FOR A LANTERN GLOBE

Berwin W. Jacobs, Rochester, N. Y., assignor to
Star Headlight & Lantern Co., Inc., Rochester,
N. Y.

Application May 29, 1948, Serial No. 146,678

Term of patent 14 years

(Cl. D48—24)

To all whom it may concern:

Be it known that I, Berwin W. Jacobs, a citizen of the United States, residing at Rochester, New York, have invented a new, original, and ornamental Design for a Lantern Globe, of which the following is a specification, reference being had to the accompanying drawing, forming part thereof.

In the drawing:

Fig. 1 is an elevational view shown as a partial cross-sectional view taken on the line 1—1 of Fig. 2; and

Fig. 2 is a bottom plan view of a lantern globe showing my new design.

I claim:
The ornamental design for a lantern globe, as shown.

BERWIN W. JACOBS.
